UNITED STATES PATENT OFFICE

92,288

DESIGN FOR A FLEXIBLE POCKET RECEPTACLE

Warner R. Buxton, Longmeadow, Mass.

Application December 22, 1933, Serial No. 50,182

Term of patent 14 years

To all whom it may concern:

Be it known that I, WARNER R. BUXTON, a citizen of the United States, residing at Longmeadow, in the county of Hampden, and State of Massachusetts, have invented a new, original, and ornamental Design for Flexible Pocket Receptacles, of which the following is a specification, reference being had to the accompanying drawing, forming part thereof.

Fig. 1 is a top plan view of a flexible pocket receptacle in which my new design is embodied; and

Fig. 2 is a front elevational view of the flexible pocket receptacle showing the design.

The design appears wholly on the front side

of the flexible pocket receptacle shown in Fig. 2, the reverse side being plain. The characteristic feature of the design resides in a plurality of lines, defining the top edges of the pockets, diverging from a point adjacent the upper outer corner of the pockets and a plurality of lines, defining the side edges of the pockets and diverging from a point adjacent the diagonally opposite corner of the pockets, the lines defining the top and side edges of each pocket meeting above the diagonal joining said corners.

I claim:

The ornamental design for a flexible pocket receptacle substantially as shown and described.

WARNER R. BUXTON.
